CONTROL MEANS FOR HYDRAULIC PRESS
OPERATING CIRCUITSWalter Ernst, Mount Gilead, Ohio, assignor, by
mesne assignments, to The Hydraulic Press
Corporation, Inc., Wilmington, Del., a corpora-
tion of Delaware

Application September 13, 1932, Serial No. 632,980

7 Claims. (Cl. 60—52)

This invention relates to control means for hydraulic press operating circuits, and more particularly to control means for press operating circuits including variable discharge pumps.

- 5 Pumps of this general description are of various constructions, and, generally stated, the present invention relates in part to control mechanism adapted for use in connection with a number of different types of variable discharge pumps.
10 For the purposes of illustration one embodiment of the invention will be disclosed in connection with a pump of the radial, reversible, variable discharge kind now well known in the art.

Pumps of this kind are exemplified by the pump disclosed in the patent to Elek K. Benedek, No. 1,964,244, issued June 26, 1934. Briefly stated, such pumps include a plurality of radially arranged cylinders and pistons, the rate and direction of discharge effected by which depend upon the eccentricity of the cylinders or pistons relative to each other. The cylinders or pistons usually are adapted to be positioned by a floating ring or the like, which, by means of a control element, may be shifted to vary the eccentricity of the cylinders or pistons and thereby to effect control of the pump discharge. Various other kinds of variable discharge pumps are known in the art, and it will be understood that the present invention relates to control mechanism for use in connection with pumps differing in some respects from the pump illustrated herein.

More specifically the present invention relates to a novel arrangement of servo-motor control means for varying the rate of discharge and/or reversing the direction of discharge of a pump of the general character referred to so that an improved and simplified arrangement of press-operating circuit and fluid pressure supplying pump may be had.

40 An object of the invention is to provide a simple and efficient control mechanism of the general character stated.

Another object is to provide, in such a control mechanism, novel means for limiting adjustably the maximum rate of discharge of the pump and the maximum discharge pressure thereof, the arrangement being such that each adjustment can be made without disturbing the other.

A further object is to provide an improved and simplified servo-motor control for a pump connected in circuit with a hydraulic press. Other objects will become apparent from a reading of the following description, the appended claims, and the accompanying drawing, in which:

55 Figure 1 is a view partly in front elevation and

partly in vertical section of a pump and control mechanism embodying the invention, a hydraulic motor and circuit to which the pump is connected being shown somewhat diagrammatically; and

Figure 2 is a fragmentary longitudinal vertical 5 sectional view of a modified form of pump control mechanism.

A practical embodiment of the invention is illustrated in Figure 1 of the accompanying drawing as being connected to a pump A of the radial, 10 reversible, variable discharge type, the pump being connected in hydraulic circuit with a hydraulic motor or press B.

As shown, the pump A includes a casing 1, a shaft 2 which may be driven from any suitable 15 source of power, and combined intake and discharge pipes 3 and 4. The pipe 3 is connected to the upper or pressing cylinder 5 of the press B and the pipe 4 is connected to the lower or push back cylinders 6 thereof. When the pump 20 is discharging through the pipe 3, the ram 7 of the press will be moved downwardly to perform a pressing or other like operation, the pump at this time receiving its intake principally from the cylinders 6. When the pump is reversed so as 25 to discharge in the opposite direction, that is, through the pipe 4, fluid will be drawn from the cylinder 5 and delivered under pressure to the cylinders 6 to move the push back rams 8 and ram 7 to their upper positions. A compensating 30 valve 9 of the kind fully disclosed in the United States patent to Walter Ernst 1,653,350, dated December 20, 1927, is connected across the pipes 3 and 4 and has its central chamber 10 connected to a tank 11 by means of a pipe 12 for compensating for the unequal effective cross sectional areas of the cylinder 5 and the cylinders 6 in a manner well understood in the art.

The pump A includes a floating ring 13 mounted in the casing 1, this ring being movable radially with respect to the pump shaft for varying the pump discharge. A rod 14 is connected to the ring 13 and extends through a packed opening 15 in one side of the casing. A cylinder body 16 is mounted on the pump casing and is formed with cylinder chambers 17 and 18 separated by a dividing wall 19. The outer end of the rod 14 is enlarged to provide a resultant shoulder 20 disposed in the cylinder chamber 17, the enlarged part of the rod being fitted for sliding movements 50 within the bore defined by the dividing wall 19, and the extreme outer end of the rod being provided with a piston 21 fitted for sliding movements within the cylinder chamber 18. The outer end of this chamber is closed by a cover 22 pro- 55

- vided with a vent 23. For a purpose to be described later, the cylinder body is formed with a port 23^a which opens into the cylinder 18 adjacent but slightly spaced from the inner end of the cylinder, and with a port 23^b which opens into the cylinder 18 at its extreme inner end. A check valve 23^c is located in the port 23^b and is adapted to permit flow through the port inwardly towards the cylinder 18 but not in the reverse direction.
- 10 In the embodiment of the invention illustrated in Figure 1, a rod 24 is connected to the ring 13 on the side opposite the rod 14 and is provided with an enlarged part 25 forming a resultant shoulder 26, the enlarged part 25 being mounted 15 for sliding movement within a bore 27 formed in the pump casing. The pump casing is likewise provided with a counter bore 28 through and beyond which the outer end of the rod 24 extends. A guide bracket 29 is secured to the pump casing 20 and is provided with an internally threaded opening for the reception of an externally threaded sleeve 30 provided with a bushing 31 which receives the rod 24 for sliding movements. The inner end of the sleeve 30 is adapted to cooperate 25 with the shoulder 26 on the rod for limiting movement of the latter to the left in order to fix definitely the maximum rate of discharge by the pump. By rotating the sleeve 30 within the opening in the bracket 29, the position of the sleeve 30 with respect to the pump casing may be changed and the rate of discharge limit thereby varied. A lock nut 32 having threaded connection with the sleeve 30 is adapted to lock the sleeve in adjusted position.
- 30 The outer end of the rod 24 is threaded as at 33 for the reception of a hand wheel nut 34 the inner face of which has cooperative connection with a spring seat 35 through the medium of an anti-friction bearing 36. A spring 37 is mounted 35 in surrounding relation to the rod 24 and is interposed between the spring seat 35 and the inner end of the bracket 29 adjacent the sleeve 30. A guide member 38 is secured to the spring seat 35 and is mounted for sliding movements within the bracket 29 for cooperating with the latter to assist in maintaining the rod 24 against flexing and for enclosing the spring 37 against the entrance of dust.
- 35 As will be described later, fluid pressure may be admitted to the cylinder 18 for moving the piston 21, the rod 14, and the ring 13 to the right to cause the pump to discharge through the pipe 4 and the push back cylinders 6 to cause a return stroke of the platen. If, now, the fluid pressure 40 in the cylinder 18 is relieved, the spring 37 will move the rod 24 to the left until the shoulder 26 on the rod engages the inner end of the sleeve 30, whereupon movement of the rod 24 and the ring 13 to the left will be arrested, the sleeve thereby 45 constituting a stop for limiting definitely the maximum rate of discharge by the pump through the pipe 3. By adjusting the position of the sleeve 30 to the right, the maximum rate of discharge of the pump through the pipe 3 can be 50 reduced. For example, if the sleeve 30 is moved to the right so that its inner end will be disposed approximately half way between the inner and outer ends of the counter bore 28, the maximum rate of discharge of the pump will be approximately half of the maximum discharge of the pump when the sleeve 30 is in the position shown in Figure 1, in which position the greatest maximum discharge of which the pump is capable may be had.
- 55 If it is desired to limit the maximum discharge

pressure as distinguished from rate of discharge, the hand wheel 34 may be rotated on the rod 24 to position the spring seat 35 to the right of its Figure 1 position to raise the maximum discharge pressure, or to the left of its Figure 1 position to decrease the maximum discharge pressure. It will be observed that the sleeve 30 may be adjusted to vary the maximum rate of discharge without effecting the adjustment of the maximum discharge pressure, and that the hand wheel 34 10 may be adjusted to vary the maximum discharge pressure without disturbing the adjustment of the maximum discharge rate as determined by the position of the sleeve 30.

For supplying fluid pressure to the cylinder 18 15 for moving the piston 21 and the ring 13 to the right, a source of fluid pressure and means for controlling the application of pressure from such source to the cylinder is provided. In the illustrative embodiment of the invention, a low 20 pressure pump 39 is employed as a source of pressure referred to. This pump is arranged to receive fluid from the tank 11 through a suction pipe 40 and to discharge fluid into the cylinder 18 through the medium of a pipe 41 which provides 25 constant communication between the discharge side of the pump 39 and the outer ends of the ports 23^a and 23^b, which communicate with the cylinder 18. A branch pipe 42 leads from the pipe 41 to a control valve generally designated 43 30 mounted on the press head, and thence through a pipe 44 to the tank 11. The control valve 43 includes a casing 45 provided with a central bore in which is mounted a piston valve 46, the casing being formed with chambers 47 and 48 both communicating with the central bore and communicating respectively with the pipes 42 and 44, a control bore portion 49 intervening between the chambers 47 and 48 in the valve casing. The piston valve 46 comprises spaced heads 50—51 40 slidably within the central bore, and the head 50 normally is positioned in the bore portion 49 intervening between the chambers 47 and 48 so as to cut off communication between the chambers. When the piston valve is moved upwardly 45 to the position shown in Figure 1, communication between the chambers 47 and 48 is established, so that fluid may flow from the pipe 42 through the control valve and the pipe 44. It is desirable, in order that delicate control of the operation of 50 the press may be effected, for the rate of flow of fluid through the control valve to be susceptible to variation in small increments by comparatively large movements of the piston valve. To this end the head 50 of the piston valve is formed at 55 its lower end with a V notch 52. Obviously, when the valve is moved from its closed to its open position, the first flow of fluid will take place through the top of the V notch and will be quite small. Further upward movements of the piston 60 valve will result in very small increases in the rate of flow until the head 50 has cleared the bore portion 49 completely.

The lower head 51 of the valve extends down through packing 53 in the bottom end of the 65 casting and is connected by a collar 54 with an operating rod 55 which extends through an arm 56 connected to the ram and through a guide bracket 57 on the press base. A spring 58 is interposed between the arm 56 and the collar 54 70 for transmitting motion to the operating rod and valve when the ram approaches the limit of its upward travel.

For controlling the position of the piston valve 75 manually, a hand lever 59 is pivoted on a bracket

60 carried by the press base and is provided with an arm 61 having a rounded end disposed between collars 62—62 secured to the lower end of the operating rod 55.

5 As will be described in detail hereinafter, the piston valve 46 is in a position below that shown in Figure 1 at certain stages of the operation, so that no flow can take place through the bore portion 49 connecting the chambers 47 and 48 wherein by pressure is applied through the pipe 41 to the piston 21 in the cylinder 18. During such stages of operation, it is necessary that the fluid discharged by the pump 39 be returned to the tank 11, and for accomplishing this purpose a relief 10 valve is connected in parallel with the valve controlled bore portion 49. In the form shown, the relief valve is incorporated in the casing of the control valve 43. As shown, the valve casing 48 is provided with a passage 63 disposed between 15 the chambers 47 and 48. A plunger valve 64 has its lower end mounted for sliding movements in the passage 63 and has a head 65 enclosed within a spring chamber 66, the head and valve being held down by a spring 67 interposed between the 20 head and a cap 68 having threaded connection in the casing 45 at the upper end of the spring chamber. In operation, when the bore 49 is closed and when the piston 21 has been moved to its extreme right hand position so that there can be no further flow of fluid through the pipe 41, fluid pressure in the chamber 47 will raise the spring loaded 25 plunger valve, whereby fluid will be by-passed through the passage 63 and thence into the chamber 48 and through the pipe 44 to the tank 11, the pipe 42, the valve 43, and the pipe 44 thereby 30 constituting an exhaust conduit connected between the cylinder 18 and the tank 11. In order that the maximum pressure of the fluid discharged by the pump A will not exceed a predetermined value, a branch pipe 69^a is connected 35 between the pipe 3 and the cylinder chamber 17, the arrangement being such that the shoulder 20 on the rod 14 will be acted on by the same unit pressure as exists in the pipe line 3 and the press- 40 ing cylinder 5 at all times.

45 In order that the cooperative relation of the various parts of the arrangement described above be clear, a complete operating cycle will be set forth briefly. It will be assumed that the parts 50 are in the positions shown in Figure 1 and that the pumps A and 39 are being driven. The ram is in its upper position wherein the arm 56 cooperates with the spring 58 to maintain the piston valve 46 elevated so as to provide communication 55 between the valve chambers 47 and 48 through the medium of the bore 49. The communication through the bore 49 is restricted so that the pump 39 will discharge against back pressure which will act through the pipe 41, the ports 23^a and 23^b, 60 and on the piston 21 so as to maintain the ring 13 in a substantially neutral or zero discharge position against the urge of the spring 37 which tends to move the ring 13 to the left. In order to produce a down stroke of the ram, the hand lever 59 65 will be turned in a counterclockwise direction, thereby raising the piston valve to such a position as to permit substantially unobstructed flow through the bore portion 49. This will permit free by-passing of fluid from the pump 39 through the 70 pipe 42, the valve chamber 47, the bore portion 49, the valve chamber 48, and the pipe 44 to the tank 11, so that the pressure in the pipe 41 and cylinder 18 will drop, after which the spring 37 75 will move the rod 24 and the ring 13 to the left so as to cause the pump to discharge through the

pipe 3 into the cylinder 5 and to initiate the downward movement of the ram.

If it is desired that the ram move slowly on its downward stroke, the hand lever 59 is manipulated so as to cause a slight throttling of the fluid passing through the bore 49. This will result in the building up of back pressure in the pipes 42 and 41 and the cylinder 18, this building up of back pressure being dependent upon the degree of throttling effected. This back pressure, acting 10 on the piston 21, will move the latter and the ring 13 toward the right against the urge of the spring 37 so as to reduce the rate of discharge of the pump through the pipe 3. It will be seen that, by shifting the piston valve to effect different degrees of throttling of fluid flowing through the bore 49, it is possible to create any desired back pressure in the cylinder 18, and that to each back pressure thus created there belongs a definite corresponding spring pressure which will balance 15 the back pressure and which will hold the ring 13 in a definite position. Any slight change in the position of the piston valve will result in a corresponding change in the position of the ring 13, so that the rate of discharge by the pump 20 may be varied readily.

When the ram encounters the work so that pressure builds up in the cylinder 5, this pressure will act through the pipe 69^a and in the cylinder 17 to move the rod 14 and the ring 13 to their 30 neutral positions so as to limit the maximum pressure of fluid discharged by the pump. This pressure may be varied by adjusting the hand wheel 34.

When it is desired to produce a return movement of the ram, the operating lever is turned in a clockwise direction so as to lower the piston valve and to close the bore 49. This will cause immediately the building up of a back pressure in the pipes 42 and 41 and the cylinder 18, resulting 40 in movement of the piston 21 and the ring 13 to the right against the urge of the spring 37, thereby reversing the flow of fluid through the pump so that the latter will discharge through the pipe 4 into the push back cylinders 6 to start 45 the ram on its upward movement. When the piston 21 has been moved to its extreme right hand position, the pressure responsive relief valve 64 will open to permit by-pass of fluid from the pipe 42 through the chamber 47, the passage 63, the chamber 48, and the pipe 44, it being understood, however, that, because of the relief valves being spring loaded, sufficient back pressure will be maintained to hold the piston 21 in its right hand position against the urge of the spring 37. 50

55 As the ram approaches the end of its return stroke, the arm 56, acting through the spring 58 and the collar 54, will raise the piston valve so as to permit more free flow of fluid through the bore 49 and to reduce the pressure acting on the piston 21, thereby permitting the spring 37 to move the ring 13 toward neutral. The ram finally will come to rest preventing further opening of the piston valve. The ram normally will be maintained at rest in its upper position, but if there is a tendency for the ram to drift downwardly there will result a lowering of the piston valve and a further throttling of the bore 49, whereby back pressure again will build up in the pipes 42 and 41 and the cylinder 18, causing the piston 21 to move the ring 13 to the right just enough to result in a slight discharge through the pipe 4. The ram then will be moved upwardly until it reaches its at rest position. 60

65 Referring more particularly to the ports 23^a 70 and 23^b 75

and 23^b which afford communication with the cylinder 18, it will be noted that, when the piston 21 is moved to the left quickly under the urge of the spring 31 after the piston valve 46 is opened quickly, fluid will be entrapped between the left hand face of the piston and the adjacent end of the cylinder after the piston covers the inner end of the port 23^a. Since the fluid cannot escape through the check valve controlled port 23^b, the entrapped fluid will serve to cushion the piston 21 and to bring it to rest without the occurrence of shocks. When pressure builds up in the pipe 41 after the piston valve 46 has been closed, the check valve 23^c will open so as to permit fluid 10 to flow through the port 23^b into the left hand end of the cylinder 18 so as to move the piston to the right.

Figure 2 illustrates a modification of the means for adjustably limiting the maximum rate of discharge and the maximum discharge pressure of the pump. In this modification the floating ring 13, the rod 24 connected thereto and provided with an enlarged part 25 forming a shoulder 26, and the casing bore 27 in which the rod is mounted 20 for sliding movements are the same as those parts as disclosed in Figure 1. In the Figure 2 construction, a bracket 69 bolted to the pump casing is provided with an inwardly extending flange 70 which receives for sliding movements a sleeve 71 25 the inner end of which is provided with a peripheral flange 72 adapted to cooperate with the flange 70 to limit the movement of the sleeve to the left, the flanges 70 and 72 constituting stops. The sleeve 71 is threaded as at 73 for the reception 30 of a hand wheel equipped nut 74 which has cooperative connection with a spring seat 75 through the medium of an anti-friction bearing 76, the spring seat including a guide portion 77 arranged for sliding movements within the guide bracket 69. A spring 78 is mounted in surrounding relation to the sleeve 71 and is interposed between the spring seat 75 and the flange 70 of the bracket 69.

The rod 24 is slidable within the sleeve 71 and 45 is threaded at its outer end as at 79 for the reception of a nut 80 keyed to a hand wheel 81. The nut 80 is provided at its inner end with a peripheral flange 82, the inner face of which abuts against the end of the sleeve 71 and the outer 50 face of which is in engagement with the inwardly directed flange 83 of a coupling nut 84 secured to the sleeve 71, whereby the nut 80 may rotate with respect to the sleeve 71 but is held against axial movement with respect thereto.

55 In operation, the spring 78 tends to move the sleeve 71 to the left and the end of the sleeve, acting on the nut 80, will tend to move the latter and the rod 24 to the left. The extent to which the rod 24 can be moved to the left under the urge of the spring is dependent upon the adjustment of the nut 80 axially with respect to the rod 24. This is due to the fact that, when the flange 72 on the sleeve 71 engages the flange 70 on the bracket 69, there can be no further movement of the sleeve to the left, and hence no further movement of the rod 24. The position to which the rod 24 has been moved when the flange 72 engages the flange 70 therefore depends on the relative axial adjustment of the nut 80 with 60 respect to the rod 24. If it is desired to vary the maximum discharge pressure, the load on the spring 78 is changed by rotating the hand wheel nut 74, it being observed, however, that this adjustment of the spring loading does not change 65 or in any way affect the adjustment determining

the maximum rate of discharge. Similarly, the maximum rate of discharge can be changed by rotating the hand wheel 81 without affecting in any way the adjustment of the maximum discharge pressure.

From the foregoing it will be apparent that my improved control means not only is of simple construction but also is capable of effecting very accurate servo-motor control of a variable discharge pump whereby a ram connected in circuit 10 with the pump can be operated under delicate control of speed and pressure. The importance of the advantage due to the entirely independent adjustments of maximum discharge rate and maximum discharge pressure will be apparent 15 to those skilled in this art. The circuit and control apparatus disclosed herein may be used in connection with various specific kinds of pumps other than that illustrated herein, and it will be understood that numerous changes may be made 20 in the specific construction and relative arrangement of the parts without departing from the spirit of the invention as defined in the claims.

I claim:

1. In combination in a hydraulic circuit, a 25 fluid-actuated machine, a variable delivery pump connected thereto and having a shiftable flow-control element, pressure responsive shifting means connected to said shiftable element, a source of fluid pressure uninterruptedly connected 30 to said shifting means, and a normally-closed valve in a conduit leading from said source, said valve being arranged to be operated manually and also by movement of an element of said machine and adapted to alter the pressure therein slowly 35 during the first part of its stroke and more rapidly during the remainder thereof so as to consequently alter the position of said shifting means and the delivery of said pump.

2. In combination in a hydraulic circuit, a 40 fluid-actuated machine, a variable delivery pump connected thereto and having a shiftable flow-control element, pressure responsive shifting means connected to said shiftable element, a source of fluid pressure uninterruptedly connected to said 45 shifting means, and a normally-closed valve in a conduit leading from said source, said valve being arranged to be operated manually and also by movement of an element of said machine and adapted to alter the pressure therein more rapidly at one part of its stroke than at another part so as to consequently alter the position of said shifting means and the delivery of said pump.

3. In combination in a hydraulic circuit, a 55 hydraulic machine with a reciprocating ram, a variable delivery pump having hydraulic connections only therewith and having a shiftable flow-control element, fluid pressure responsive shifting means connected to said shiftable element, said shifting means being operated in one direction only by said fluid pressure and urged in the opposite direction by yielding means, and a control valve for controlling the operation of said shifting means mounted on said machine and 60 arranged when shifted at an even speed to pass fluid therethrough more rapidly at one part of its stroke than at another part thereof, said control valve being adapted to be operated manually and also automatically by said ram.

4. In combination in a hydraulic circuit, a fluid-actuated machine, a variable delivery pump connected thereto and having a shiftable flow-control element, pressure responsive shifting means connected to said shiftable element, a 75

source of fluid pressure uninterruptedly connected to said shifting means, and a normally-closed valve in a conduit leading from said source, said valve being arranged to be operated manually and also by movement of an element of said machine and adapted when opened at an even speed to pass the fluid therethrough at an accelerated rate of quantity delivery during one part of its stroke and at a constant rate of quantity delivery during the remainder of its stroke so as to consequently alter the position of said shifting means and the delivery of said pump.

5. In combination in a hydraulic circuit, a fluid-actuated machine, a variable delivery pump connected thereto and having a shiftable flow-control element, pressure responsive shifting means connected to said shiftable element, a source of fluid pressure uninterruptedly connected to said shifting means, and a normally-closed valve in a conduit leading from said source, said valve being arranged to be operated manually and also by movement of an element of said machine and adapted when opened at even speed to pass the fluid at differently-accelerated rates of quantity delivery during different parts of its stroke so as to consequently alter the position of said shifting means and the delivery of said pump.

6. In combination in a hydraulic circuit, a fluid-actuated machine, a variable delivery pump connected thereto and having a shiftable flow-control element, pressure responsive shifting means connected to said shiftable element, a source of fluid pressure uninterruptedly connected

to said shifting means, and a normally-closed valve in a conduit leading from said source, said valve being arranged to be operated manually and also by movement of an element of said machine and adapted when opened at an even speed to permit a regular increase of the rate of quantity delivery of fluid passed up to a certain point and then to change to a different quantity rate of delivery so as to consequently alter the position of said shifting means and the delivery of said pump.

7. In combination in a hydraulic circuit, a fluid-actuated machine, a variable delivery pump connected thereto and having a shiftable flow-control element, pressure responsive shifting means connected to said shiftable element, a source of fluid pressure uninterruptedly connected to said shifting means, and a normally-closed valve in a conduit leading from said source, said valve being arranged to be operated manually and also by movement of an element of said machine and said valve having a piston valve member with an enlarged port-controlling portion abutting a reduced portion, the shoulder therebetween being provided with a V-notch whereby said valve when opened at an even speed passes fluid at a slowly increasing quantity rate of delivery during the first part of its stroke and afterward at a different regular rate so as to consequently alter the position of said shifting means and the delivery of said pump.

WALTER ERNST.
